UNITED STATES PATENT OFFICE.

RICHARD J. EDWARDS, OF GALENA, ILLINOIS.

CAR-COUPING.

SPECIFICATION forming part of Letters Patent No. 410,080, dated August 27, 1889.

Application filed May 6, 1889. Serial No. 309,772. (No model.)

To all whom it may concern:

Be it known that I, RICHARD J. EDWARDS, a citizen of the United States, residing at Galena, in the county of Jo Daviess and State of Illinois, have invented certain new and useful Improvements in Car-Couplings, of which the following is a specification, reference being had therein to the accompanying drawings, in which—

10 Figure 1 represents a bottom view of one end of a passenger-car provided with my improvements, and Fig. 2 a vertical sectional view of the same.

The invention has relation to certain new and useful improvements upon that class of railway pipe-coupling covered by Patent No. 400,759, issued to me on the 2d day of April, 1889; and it has for its object, particularly, to adapt the same for employment upon passenger-cars, as will be more fully hereinafter specified.

Referring to the annexed drawings by letter, A designates the air or steam conducting pipe, attached to the bottom of the car and provided with a stop-cock *a* and a flexible hose-section *b*, this flexible section having attached to its forward end a coupling *c*. Journalled in suitable bearings upon the bottom of the car-beams is a transverse rock-shaft *B*, provided at its ends with operating-handles *d* and at suitable points intermediate its ends with crank-arms *e* and *f*. Connecting the crank-arm *e* to an upwardly-extending arm upon the coupling *c* is a chain 35 *g*, which passes over a suitable pulley secured to the bottom of the car, near the forward end of the same. Connected to the chain *g*, and extending up through an aperture formed in the front platform of the car, 40 is another chain *g'*, which is provided with an operating ring or handle *j* at its upper end, and which preferably passes over a roller *h*, journalled in the said aperture, through which the said chain passes. The 45 flexible hose-section *b* is preferably braced by means of an arm *i*, bolted rigidly to the bottom of the car.

The coupling *c* is constructed and operated in substantially the same way as in my former patent hereinbefore referred to.

The stop-cock *a*, which controls the pas-

sage of air and steam through the main conducting-pipe, is provided with an arm *a'*, which is connected to the crank-arm *f* by means of a chain *k*, which passes over two 55 pulleys secured upon the bottom of the car—one *l* forward of the crank-shaft and the other *l'* to the rear thereof. When the stop-cock is open, the arm or lever *a'* is turned down, as shown in Fig. 2, and when closed it is turned 60 up in a horizontal position, as shown in Fig. 1.

Connected to the chain *k* at a suitable point forward of the crank-shaft is another chain *k'*, which passes up over a pulley or roller *h'*, journaled in an aperture in the 65 platform of the car, alongside the roller *h*, and which is provided with a ring or handle *j'* at its upper end.

To prevent meddling with the rings *j j'*, a pivoted guard *C* is placed over the same, as 70 shown in Fig. 2, the guard being held in place over the rings by means of a suitable staple and lock.

Pivoted to a rod *D*, secured to one of the car-beams, is a stout hook *E*, which is adapted 75 to hook into a safety-chain attached to the adjacent car. To unhook the hook *E* from the safety-chain, a chain *m* is attached to it and connected to the chain *k* at a suitable point in its length, the said chain *m* passing 80 over an intermediate pulley *n*, secured to the bottom of the car.

The couplings *c* are connected in the same manner as in my former patent.

When it is desired to uncouple the hose-sections of two connected cars, the crank-shaft *B* is first rocked in a forward direction, which action, through the medium of the chains *k* and *m*, close the stop-cock *a* and unhook the hook *E* from its safety-chain, as is 90 evident. Then the shaft is rocked in the reverse direction and the hose-couplings uncoupled through the medium of the chain *g*. Should it be desired to operate the devices from the platform of the car, the chains *g'* 95 and *k'* are employed, thus avoiding the necessity of dismounting from the car.

It is evident that the lever *a'* may be arranged so as to work in a horizontal plane instead of in a vertical plane, as shown, without departing from the invention.

Having thus fully described my invention,

what I claim, and desire to secure by Letters Patent, is—

1. The combination, with a car provided with a conducting-pipe, a stop-cock in said pipe, and a flexible section attached to the said pipe and provided with a hose-coupling, of a multiple crank-shaft journaled upon the car, chains connecting the crank-arms respectively to the coupling and stop-cock, and independent chains g' and k' , connected to the said chains and extending up to the platform of the car, substantially as described.
2. The combination, with a car, a conduct-

ing-pipe, a stop-cock in this pipe, an arm attached to this stop-cock, a safety-hook E , pivotally attached to the car, of a crank-shaft journaled upon the car, and chains k and m , connecting the crank-arm on the said shaft to the said safety-hook and stop-cock arm, substantially as described.

In testimony whereof I affix my signature in presence of two witnesses.

RICHARD J. EDWARDS.
